(57) **CLAIM**

The ornamental design for a needle holder, substantially as shown and described.

DESCRIPTION

FIG. 1 is a perspective view of a needle holder showing my new design. The broken line showing of the safety shield is for illustrative purposes only and forms no part of the claimed design.;

FIG. 2 is a top plan view thereof;

FIG. 3 is a front elevational view thereof;

FIG. 4 is a side elevational view thereof; and,

FIG. 5 is a bottom plan view thereof.
